Attorney.

UNITED STATES PATENT OFFICE.

EDGAR STURDY RAYNER, OF HORNSEA, ENGLAND.

RAIL FASTENING.

1,402,655.

Specification of Letters Patent. Patented Jan. 3, 1922.

Application filed July 12, 1921. Serial No. 484,249.

To all whom it may concern:

Be it known that I, EDGAR STURDY RAYNER, a subject of the King of Great Britain, residing at Hornsea, in the county of York, 5 England, have invented certain new and useful Improvements in Rail Fastenings, of which the following is a specification.

This invention relates to railway and tramway permanent ways, and it has for its 10 objects, improved means for fastening flanged railway and tramway rails to metallic sleepers, jointing the rails and anchoring the joints to the sleepers, my said improved means allowing of free expansion and contraction of the rails.

With these objects in view, the invention resides in the construction and novel combination and arrangement of parts herein-after more fully described, illustrated in 20 the accompanying drawings and pointed out in the claims hereto appended, it being understood that various changes in the minor details of construction may be resorted to without departure from the spirit or sacrificing any of the advantages of the invention.

In the accompanying drawing, Fig. 1 represents a broken plan view of a metal sleeper showing the clips and clamping plates and 30 the ribs against which the inner ends of the clamping plates abut when such clamping plates are turned to the position to secure the rails on the sleeper, and also shows one of the rails secured to the sleeper; Fig. 2 is a side view of the sleeper but with the clamping plates removed; Fig. 3 is a side view of 35 a rail joint secured on a sleeper, the sleeper and clamping plate being shown in section, Fig. 4 being a similar view to Fig. 3 but 40 looking at the opposite side of the joint. Fig. 5 is a vertical section taken at right angles to the rails approximately through the longitudinal centre of a portion of a sleeper, through one of the clamping plates, through 45 one of the rails and the fish-plates and through one of the fixed clips on the sleeper. Fig. 6 represents a plan view and a side respectively of one of the clamping plates, Fig. 7 a side elevation and end elevation re- 50 spectively of the inner fish-plate of the two fish-plates employed for connecting adjoining ends of two lengths of rail, and Fig. 8 a side elevation and end elevation respec-

tively of the outer fish-plate of the two fish-plates referred to.

Fig. 6 is drawn to a larger scale than the other figures.

Similar reference characters indicate like or corresponding parts throughout the several figures of the drawings.

Referring to the drawings, A is the metal sleeper which is conveniently pressed out of steel or iron, a, a are two clips near one end and a¹, a¹ two other clips near the other end thereof, the said clips being either formed by making suitable incisions in the top of the sleeper and pressing outwardly the portions within the incisions, or by riveting or otherwise securing metal pieces of the required shape to the top of the sleeper, one of these two arrangements of clips being adapted to pass over and engage the outer flange of one rail A¹ of the pair of rails, the other arrangement being adapted to pass over and engage the outer flange of the other rail (not shown) of the pair of rails, the distance between the two arrangements of clips being that of the gauge of track required.

B and B¹ are two clamping plates permanently pivotally attached to the sleeper each by a rivet or pivot pin b, the said clamping plates having eccentrically rounded ends, and each having an upwardly projecting portion or lip b¹ set back a little distance from one end, the portion of each plate at the outside of the upwardly projecting portion or lip constituting a tongue b², and b³ is a circular recess in the underside of each clamping plate.

C, C are two transverse ribs or shoulders each formed by pressing upwardly a portion of the sleeper, or by means of a piece of metal riveted or otherwise suitably secured to the top of the sleeper, and D, D are two paps or small protuberances pressed out of or secured to the top of the sleeper and which engage the one the recess in the clamping plate B and the other the recess in the clamping plate B¹ when such clamping plates are turned to the position to secure the rails on the sleeper.

E is a fish-plate secured to the inside face of the web of the rail where the ends of two lengths of rail meet, the said fish-plate having a suitably long gap e at the bottom between its two ends to allow the tongue b²

on the end of the clamping plate which assists in securing the rail to the sleeper to pass through the fish-plate and press on the inner flange of the rail and against the web 5 of the rail, E^1 being a similar fish-plate secured to the outside face of the web of the rail and parallel with the fish-plate E , the said fish-plate E^1 being provided with a gap e^1 corresponding with the gap in the fish-plate E to allow of the clips a, a , or a^1, a^1 as the case may be, entering the gap and engaging the outer flange of the rail, such fish-plate E^1 being provided with two outwardly 10 projecting portions or stops e^2 , one at each end of the gap, which stops, limit the movement of the fish-plate across the sleeper within the extent of the gap and prevent it from passing over the fixed clips.

F, F are bolts which pass through the 20 fish-plate E , through the web of the rail and through the fish-plate E^1 and secure the two fish-plates to the two lengths of rail to be connected, the holes a^2, a^3 through the web of the rail through which these bolts 25 pass being elongated or otherwise larger than the diameter of the said bolts to allow of contraction and expansion of the rail.

It will be understood that the fish-plates are only employed at the meeting ends 30 of two lengths of rail and are for connecting such two lengths or rail portions together.

To secure the rails to the sleeper, the rails are laid on the sleeper with the outer flange 35 of one rail engaged by the clips a, a and the outer flange of the other rail (not shown) engaged by the clips a^1, a^1 , the clamping plate B is turned at right angles or thereabouts to the rail it is to secure, until its 40 inner rounded end abuts against the rib or shoulder C on the sleeper and the tongue b^2 at its other end passes through the gap e in the fish-plate E and passes over and bears on the inner flange and its outer end 45 against the web of the rail, and the upturned portion or lip b^1 presses on the inner fish-plate when the portion of the rail on the sleeper is a jointed portion, the said tongue of the clamping-plate tightening on the inner flange of the rail and by bearing 50 firmly thereon and its end pressing against the web of the rail, forms a combined clamp and wedge, so firmly clamping the rail to the sleeper, the rail being held by the clips a, a on the sleeper engaging the outer flange and the tongue on the clamping plate engaging and pressing on the inner flange and on the web of the rail, the other and par-

allel rail being held on the sleeper in like manner by the clips a^1, a^1 and by the clamping plate B^1 .

When the clamping plates are turned to the position for the tongues b^2 to engage the inner flanges and press against the webs of the rails, and, where fish-plates are employed, for the upturned portions or lips b^1 to press on the inner fish-plates, the paps or small protuberances D, D on the sleeper enter and engage the recesses b^3 in the underside of the clamping plates and so prevent the clamping plates from turning by the action of vibration, expansion and contraction or other unintentional cause once such clamping plates have been properly fixed in the locking position.

Having thus described my invention, what I claim and desire to secure by Letters Patent is:—

1. In a rail fastening, a tie provided with a rail clip device and an abutment, a clamping plate pivoted to the tie and adapted to press against one side of the rail and against the said abutment and thereby clamp the rail against the said clip device, and means for locking the clamping plate to the tie in the clamped position.

2. The combination, with a tie provided with a rail clamping device and an abutment, of rails, a fish-plate connecting the said rails and having a recess which permits the said clip device to engage directly with the rails, and a clamping plate pivoted to the tie and adapted to press against the rails and against the said abutment and clamp the rails against the said clip device.

3. The combination, with a tie provided with a rail clip device and an abutment, of rails, a fish-plate connecting the said rails and provided with a recess at its lower part, and a clamping plate pivoted to the tie and adapted to engage directly with the rails and with the said abutment and clamp the rails against the said clip device.

4. The combination, with a tie provided with a rail clip device and an abutment, of rails, a fish-plate connecting the said rails and provided with a recess at its lower part, and a clamping plate pivoted to the tie and provided with lips adapted to engage with the rails and with the fish-plate respectively, said plate being also adapted to bear against the said abutment and to clamp the rails against the said clip device.

In testimony whereof I affix my signature

EDGAR STURDY RAYNER
